CLAIM

The ornamental design for a feed roller, as shown and described.

DESCRIPTION

FIG. 1 is an upper perspective view of a feed roller including an outer surface with a repeating pattern of chevron shapes according to our design;

FIG. 2 is a front elevational view of the feed roller;

FIG. 3 is a rear elevational view of the feed roller;

FIG. 4 is a left side view of the feed roller;

FIG. 5 is a right side view of the feed roller;

FIG. 6 is a top plan view of the feed roller; and,

FIG. 7 is a bottom plan view of the feed roller.

The broken lines in FIGS. 1, 4 and 5 are environmental and form no part of the claimed design of this invention.
